UNITED STATES PATENT OFFICE.

VERE LOCKSLEY REEVE, OF BALLARAT, VICTORIA, AUSTRALIA.

PRINTING PRESS.

Application filed September 28, 1921, Serial No. 503,879, and in Australia October 15, 1920.

This invention relates to an improved printing press and it refers especially to a combination printing, litho and offset press for printing on paper, cloth, tin or other material in single or a plurality of colours.

The object of the present invention is to provide a printing press of simple construction which can be easily and conveniently adapted to perform all or any of the different kinds of printing now performed on the various types of direct or offset printing presses now in use whereby one or more colours are placed side by side or superimposed on paper, cloth, tin or other materials in one or more operations of the press.

This invention is applicable to the use of blocks, plates, formes of type, stones and other impressing media or sections of the same and it will be understood that in this specification the term "formes" will include all such devices for transferring on to the offset cylinders or paper a film of ink representing the characters, designs or engravings to be printed.

I accomplish the above mentioned object by providing a printing press wherein provision is made for transferring one or more colours from one or more formes or other impressing means or sections thereof direct upon paper or other material (either side by side or superimposed) or alternately for transferring one or more colours from one or more formes or other impressing means to one or more "offset" printing cylinders in correct register or two or more colours in correct register on one offset printing cylinder and another colour or other colours on a separate offset printing cylinder whereby the colours so transferred can be printed in correct superimposed register upon paper or other material to produce multi-colour work.

The means for carrying the invention in effect comprises briefly a frame having a reciprocatingly mounted table upon which are mounted one or more formes each having one or more superimposed inking rollers and an ink duct or reservoir for placing its own particular colour or colours of ink thereon as the table is moved forward and means for bringing the said formes on the forward movement of the table into contact with one or more offset or direct printing cylinders in such a manner that one or more

of the impressions will be transferred there to either side by side or in accurately superimposed register.

When printing direct on to the paper passing around the printing cylinder or cylinders from the formes the printing operation is performed on the forward movement of the table and when performing an offset printing operation the said offset cylinders are placed in contact with and print on the paper on the return movement of the table.

A printing press constructed in accordance with the present invention can be adapted to print upon paper or other material taken from a reel and thereby operated at a high speed or upon flat sheets of paper.

In order that my invention may be readily understood reference will now be had to the accompanying sheets of explanatory drawings wherein

Figure 1 is a view in side elevation of a printing press constructed in accordance with the present invention.

Figure 2 is a view in sectional side elevation of the table and shows means for movably supporting and for adjusting the height of the same.

Figure 3 is a view in sectional end elevation taken on the line 3—3 of Figure 2.

Figure 4 is a view in end elevation of the printing press shown in Figure 1.

Figures 5 and 6 are views in side and end elevation respectively of part of the mechanism employed for feeding paper from a reel into the press and hereinafter will be more fully described.

Figure 7 is a view in side elevation of the delivery end of the press showing parts attached thereto for feeding sheets of paper therethrough and for cutting the said sheets of paper into sections of predetermined size.

Figure 8 is a view in side elevation of part of the press showing a set of ink distributing rollers.

Figure 9 is a view in end elevation of part of the press and shows portion of the ink distribution rollers shown in Figure 8.

Figure 10 is a view in side elevation of part of the press and shows two sets of printing cylinders adapted to perform offset printing operations and means for adjusting the paper to ensure the colours being placed in correct register thereon.

Figure 11 is a view in side elevation of a

modified form of device for supporting the ends of an offset or direct printing cylinder and hereinafter will be more fully described.

Figures 12 and 13 are views in sectional side elevation and end elevation, respectively, showing portions of combined feeding and cutting devices for cutting the printed sheets transversely into sections of predetermined size.

10 Figure 14 is a view in plan of the rear part of the frame of the printing press showing portion of the table removed to clearly illustrate extensible supports for the said table.

15 Figures 15, 15^a, 15^b, and 15^c, are diagrammatic views illustrating the action of the inking and printing cylinders with relation to the position of the impressing means at different points in the movement of the table.

20 Four inking cylinders and two sets of printing cylinders are shown and arranged so that three colours are applied to one printing cylinder and one colour to the other printing cylinder.

25 Figure 16 is a diagrammatic view showing the inking rollers arranged to apply two colours to each printing cylinder.

30 In these drawings the numeral 20 designates a rectangular frame having a table 21 mounted reciprocatingly on the feed end thereof.

35 The table is made approximately half the length of the frame and is supported on rollers 22 which are adapted to run on grooved tracks 23 fitted to a lower part of the frame.

40 A driving shaft 24 is mounted transversely at the delivery end of the frame and pinions 25 on this shaft gear with spur wheels 26 on a counter-shaft 27. The spur wheels 26 are provided with a crank pin 28 to which is connected one end of a pitman 29 having its opposite end connected to the centre of a transverse shaft 30. The ends of the shaft 30 pass through and are rotatably supported in longitudinally disposed beams 31 which are fitted with laterally projecting spindles 32 carrying the rollers 22.

50 The shaft 30 is provided with a pair of gear wheels 33 which mesh with racks 34 fitted to the base of the frame and with racks 35 fitted to the underside of the table supporting frame 21.

55 The use of double racks in conjunction with the supporting rollers as above described ensures the table being moved longitudinally a distance equal to twice the stroke of the crank pin 28 at each half revolution of the spur wheel.

60 The forme carrying table is adjustably supported within the rectangular open frame 21' which is adapted to move freely between the sides of the press frame and rest upon the rollers 22. The said table is adapted to be raised and lowered to suit

the height of the blocks or other impressing media attached thereto by wedge shaped blocks 36 which are removed in unison by operating wheels or handles fitted to right and left hand threaded bars 37.

65 The surface of the table is provided with any suitable means for securing thereto a number of blocks, plates or forms of type corresponding to the number of colours desired to produce the effect required in the printing.

70 The frame of the press is provided with a number of vertical brackets 38 each of which is adapted to support journal bearings 39 for an ink distributing roller 40 80 and forme inking roller 41.

75 The journal bearings 39 for the rollers 40 are secured adjustably at any desired point in the height of the brackets by means of set-screws 42 and the normal position of the 85 journal bearings of the forme inking rollers 41 is regulated by set-screws 43.

80 The brackets supporting the journal bearings are slotted to permit of the said bearings being adjusted to a required height and 90 the bearings of the inking rollers 41 to move vertically therein.

85 The distributing roller 40 receives ink from an oscillatingly supported roller 44 which is adapted to receive its supply from a roller 45 operating in an ink duct or reservoir 46. The roller 44 is actuated in such a manner that it is maintained for a desired period in contact with the distributing roller and then with the roller in the ink duct or 100 reservoir.

90 The forme inking roller 41 of each inking set is rotated continuously (first in one direction and then in the opposite direction) by means of chain and sprocket gearing actuated by the movement of the table and the roller in the ink duct is rotated by pawl and ratchet mechanism 47 and by chain and sprocket gearing 48 from a spindle of the inking roller 41. The object in rotating the 110 roller 45 by means of pawl and ratchet mechanism is to ensure it being rotated intermittently in one direction only and thereby obviate the likelihood of ink being thrown out of the duct or the roller being flooded, 115 which would result if the said roller was rotated in a reverse direction.

95 The rollers 44 are supported rotatably in the upper ends of arms 49 fitted to shafts passing transversely across the press and depending from the ends of the said shafts are arms 49' which are connected to a rod 50 having one of its ends pivoted to an oscillating lever 51. The said lever 51 is pivoted to the frame of the press and its lower end 120 is fitted with a roller which is maintained bearing against a cam 52 on the counter shaft 27 by means of a spring 53.

100 In Figures 8 and 9 both of the arms 49 and arm 49' are shown and in Figure 1 of

the drawings the arms 49 and rollers 44 are omitted to avoid confusion.

The operation of the cam 52 causes the lever 51, connecting rod 50, and arms to be operated in such a way that the rollers 44 of the inking sets are brought into contact with the rollers in the ink reservoirs and maintained in contact therewith for a short period. The spring 53 causes the lever 51 to be operated in such a way that the rollers 44 will be moved out of contact with the rollers in the ink reservoirs and into contact with the distributing rollers 40. The cam 52 shown in the drawings has been devised to move the duct rollers so as to transfer ink from the rollers in the ink reservoirs to the distributing rollers once in each rotation of the countershaft 27. The shape of the cam 52 determines the duration of the time during which the roller 44 is kept bearing against the roller 45 and this determines the amount of ink transferred to the roller 40.

The brackets supporting the bearings for the inking and distributing rollers 41 and 40, respectively, are arranged to support pivoted hangers 54 having their lower ends shaped to support screw threaded bearings 55 which engage threaded spindles 56 on lateral distributing or spreading rollers 57. The hangers on opposite sides of each bracket are connected by tension springs 58 which ensure the said spreading rollers bearing constantly against the forme inking rollers 41.

The spreading rollers are maintained bearing against the forme inking rollers with sufficient pressure to ensure them being rotated therewith and the threaded spindles and bearings cause the said spreading rollers to be reciprocated endwise during the forward and backward movements of the table. The spreading rollers ensure the ink applied or delivered to the forme inking rollers being evenly spread over their surfaces and an even application of ink to the formes or impressing media affixed to the table of the press.

The forme inking rollers 41 of the inking sets are adapted to be raised for a certain period to receive a supply of ink from the distributing rollers 40 on both the forward and backward movement of the table and the forme inking roller 41 of each set is then lowered to its full extent to apply the ink over the surface of its respective forme or other impressing media on the table.

When the table is in its rearmost position the formes or other impressing media thereon are arranged with their forward ends directly below the centres of the forme inking rollers which are then in their lowermost positions and ready to apply ink to the said formes when the table commences its forward movement. The sides of the table are provided with linear cams 41'

which are adapted to raise each forme inking roller when the table is moved forwardly a sufficient distance to bring the rear end of each forme beneath its respective inking roller. The said linear cams 41' are made sufficiently long to ensure the forme inking rollers being maintained out of contact with any but their respective formes.

When the table is moved forward clear of the inking rollers the said rollers will descend to their normal position and on the return movement of the table the linear cams will again raise the rollers until such time as they are in position to move into contact with their respective formes. Thus, it will be understood that the forme inking rollers transfer ink to their respective formes and are raised to receive ink from their respective distributing rollers on each forward and backward movement of the table.

The raising and lowering of the forme inking rollers may be effected by tappets and cams or like devices actuated from any operative part of the press the movement of which synchronizes with the movement of the table.

The frame of the press can be provided adjacent to each inking set with suitably disposed auxiliary inking rollers (as shown at 99 in Figure 1) which may be supplied with ink by hand or in any other approved way.

In the drawings the press is shown fitted with four sets of inking rollers constructed and arranged as above described and the forme inking rollers 41 are operated through chain and sprocket gearing 59, 60 and 61 from a rotatable spindle 62 which is adapted to receive its motion from gearing 63 mounted on the machine frame and actuated by the movement of racks 64 fitted to the frame of the table.

The gearing 63 which is controlled by the movement of the table operates in one direction on the forward movement and in the reverse direction on the backward movement of the said table.

Two printing sets 65 and 65' are mounted on the forward part of the frame so that one set 65 will be disposed in advance of the table when in its rearmost position and the other set 65' is located above a forward part of the table and at the rear of one of the inking sets of rollers which is disposed between said printing sets (see Figures 1 and 16).

Each printing set comprises an offset cylinder 65^a and a paper or printing cylinder 65^b. For direct printing the offset cylinder is removed and the paper cylinder lowered to take its place.

The printing sets are so disposed that the forme or impressing media 66 on the front part of the table will be brought to bear against the offset cylinder 65^a of the set 65

whilst the formes or impressing media 67, 68 and 69 on the rear part of the table will be brought to bear against the offset cylinder 65^a of the rear set 65' when the said 5 table is moving on its forward travel (see Figures 15 to 16).

The inking rollers and printing sets can be adjusted on the frame of the press so that colours from one or more of the formes 66, 10 67, 68 and 69 on the table can be transferred to the printing set 65' and one or more colours can be transferred in a like manner to the printing set 65.

When two or more colours are transferred 15 to the offset cylinder or direct to the paper on the printing cylinder as the case may be they can be arranged side by side or be superimposed in correct register thereon.

The spindles of the offset cylinders of the 20 printing sets 65 and 65' are mounted in bearings supported movably in vertical guides or brackets 70 on the frame of the press and the paper cylinders 65^b are mounted in bearings 71 fitted adjustably to 25 the said brackets above the said offset cylinder.

The offset cylinders (or the paper cylinders in the case of direct printing) are rotated through a train of gearing 72 from 30 two sets of gearing 63 which are operated from the racks 64 fitted to the frame of the table (see Figures 1 and 3).

The impression is transferred from the 35 formes or impressing media to the offset cylinders on the forward movement of the table and when the table commences its rearward movement said offset cylinders with the impressions thereon are raised by suitable mechanism to cause them to bear against 40 the paper passing around the upper or paper cylinders and print the colours in correct register or otherwise, thereon.

When printing three or more colour designs the rear printing set can be arranged 45 to print two or more of the colours on the paper whilst the key colour or colours can be printed by the forward printing set in correct register and superimposed over the impressions printed by the rear printing set.

The means employed for raising the offset 50 cylinders into contact with the paper passing around the paper cylinders comprise adjustable connecting rods 73 having one of their ends connected to the spindles or bearings of the said offset cylinders and their 55 opposite ends connected to levers 74 pivoted to the machine frame and carrying rollers adapted to bear against cams 75. The said cams are adapted to raise the free ends of 60 the levers 74 and maintain the offset printing cylinders in contact with the paper passing around the paper cylinders for a period of time sufficient to permit of the impression being transferred to the paper.

The cams 75 are designed to permit of the

offset cylinders being lowered for a sufficient space of time to receive a correct impression from the formes on the forward movement of the table and raised for a corresponding period of time to permit of the impression being transferred to the paper on the rear movement of the table and for maintaining the said cylinders in an intermediate or neutral position at other times.

The cams 75 are driven by chain and 75 sprocket mechanism 76 from the counter-shaft in correct synchronism with the movement of the table so that the several parts will be operated in timed relationship as above described.

The connecting rods 73 are adjustable as to length by means of right and left hand threaded nuts 73' so as to permit of the offset cylinder being adjusted with respect to the paper cylinder and to the formes.

The connecting rods 73 can be slotted to engage the bearings for the offset cylinders and the said bearings can be resiliently mounted in the said slots by means of springs 77 which are capable of adjustment 90 by set screws 78 (see Figure 11). The bearings of the spindles for the train of gearing 72 are resiliently mounted (as shown at 79 in the right hand side of Figure 10) to ensure the teeth of the said gearing meshing 95 correctly when the offset cylinder is in its raised position. The strength of the springs is sufficient to support the weight of the gearing and when the offset cylinder is raised the springs raise the gearing sufficient 100 to ensure them remaining in mesh.

In order to permit of the formes or other impressing media being conveniently affixed to the table the said table is adapted to be moved beyond the rear end of the frame of the press on folding extensions of the tracks 105 23 (see Figure 14). The extensions of the tracks are indicated by the numeral 80 and are hinged to the rear ends of the main part of the said tracks. When the said extensions are placed in the positions shown in broken lines and the table is disengaged from the crank pin on the spur wheel fitted to the counter shaft it can be moved rearwardly on to the said extensions when it 110 will be easily accessible for securing the formes or impressing media thereto or for removing them therefrom.

When performing offset printing on paper taken from a spool 81 the said spool 120 is supported rotatably on a spindle mounted in brackets 82 at the rear of the machine frame. The end of the paper is passed around a fixed guide roller 83 up to and around an adjustable guide roller 84, 125 through operating feed rollers 85, across a superimposed table 86, through a pair of guide rollers 87, between the rear paper and offset cylinder, around a fixed roller 88 and an adjustable synchronizing roller 89 be- 130

tween the front paper and offset cylinders, between two fixed guide rollers 90 and thence upward to and over an adjustable roller 91, (see Figure 1).

5 The feed rollers 85 are operated with the movement of the bed by means of pawl and ratchet devices 85' and 85'' and by chain and sprocket gearing 86' and 86'' from a shaft 100 rotatably supported on the frame 10 and driven by chain and sprocket gearing 101 from the spindle of an adjacent inking roller 41.

15 The inking roller is revolved almost continuously in a backward and forward direction and in accordance with the movement of the table and the ratchet gearing 85' and 85'' ensures the paper being fed continuously in one direction through the feed rollers 85 irrespective of the direction in 20 which the inking roller is rotated.

The paper between the feed rollers 85 and the rollers 90 is moved intermittently and during the idle period of the paper (when the table is moving on its return 25 stroke) portion of the paper is looped above the table 86 by the continuous feed of the rollers 85.

30 The object of feeding the paper continuously to a point from which it can pass freely to the printing sets is to avoid any tug and tearing of the paper which would be likely to result from any intermittent rotation of the reel 81.

35 When the paper is to be printed on both sides it is passed from the roller 91 to a spool 92 upon which it is wound by gearing 93 operated from the driving shaft. The gearing 93 embodies a friction clutch or like device 93' which will permit of the 40 said gearing operating without rotating the spool 92 when the paper is passed through the press at a rate lower than the speed of rotation of the said gearing. When all the 45 paper is wound on the spool 92 the said spool is placed on the brackets 82 and the paper is passed through the press in a reversed position.

50 After printing, the paper may be cut into sheets of predetermined sizes by passing it from the roller 91 to and between feed rollers 94 above one of which is mounted a multi-blade rotary cutter 95 adapted to cut the paper transversely. In between the roller 91 and the feed rollers 94 are a number of 55 inclined knives 96 which are adapted to cut the paper longitudinally and after the paper has been cut transversely by the rotary cutter 95 the sheets can be conveyed to any desired point.

60 The paper is adjusted by means of the synchronizing roller 89 to ensure the correct superimposing of the colours or printing from the front offset cylinder over the impressions made by the rear offset cylinder 65 and the feed and guide rollers can be suit-

ably adjusted to ensure the paper being passed correctly through the machine.

When printing in four colours is desired, the inking sets are provided with the different coloured inks required and the formes 70 are arranged on the table as shown diagrammatically in Figure 15.

When the table is moved forward each forme is inked from its own particular inking roller 41 and when the rear ends of the 75 formes are brought beneath the centres of their respective inking rollers 41 the latter are raised by the linear cams 41' on the table so as to obviate them coming into contact with and transfer their colours on to 80 the next succeeding forme or formes.

In its further forward movement the table brings the inked face of the first forme and the inked faces of the remaining formes 85 consecutively into contact with the front and rear offset cylinders, respectively, and the colours are placed on the same in correct register.

When the table commences its return stroke the offset cylinders are partially 90 raised by the levers 74 and when the offset cylinders have been rotated half a revolution and the edges of the pictures or other matter being printed are brought directly beneath the centre of the paper cylinders the 95 said offset cylinders are raised by the high part of the cams 75 into contact with the paper 36' (passing round the paper cylinder) and kept bearing thereagainst until the offset cylinders have completed one revolution or part of a revolution.

100 The offset cylinders are partially lowered after transferring the impressions on to the paper and are lowered to their normal positions after the formes have all passed therebeneath when the operations above described can be repeated to make other impressions.

105 In Figure 15 the table is shown in its rearmost position and in Figure 15^a the table is shown in the position occupied when it has moved forwardly just sufficient to ensure all of the formes being inked from their respective inking rollers. In the last mentioned view the rear offset cylinder is shown receiving an impression from the second forme and the front offset cylinder in position to commence receiving an impression from the first forme.

115 In Figure 15^b the front offset cylinder is shown in its raised position after having received an impression from the first forme and the rear offset cylinder receiving an impression from the third forme.

120 In Figure 15^c the table is shown in its forward position or at the commencement of the rearward stroke with both offset cylinders in neutral position and almost into contact with their respective paper cylinders.

125 When one colour only is required to be placed on the front offset cylinder the ink-

ing sets are arranged as shown in Figure 15 and when a like number of colours are to be transferred to both offset cylinders the inking sets are arranged as shown in Figure 16
5 of the drawings.

The arrows shown in Figures 15, 15^a, 15^b, and 15^c, indicate the direction of the movement of the table.

When the press is to be employed for 10 printing direct onto the paper from the formes the offset cylinders are removed and the paper cylinder is moved to take its place. When the paper is directed through the press as above described the formes will transfer 15 their impressions direct on to the paper on the forward movement of the table and the paper cylinders will be raised prior to the commencement of the return movement of the table so as to remove the paper out of 20 contact with the said formes.

The arrangement of the printing cylinders for effecting direct printing operations is shown in Figure 7 of the drawings. In this last mentioned view the press is shown 25 adapted for printing on sheets of paper and is fitted with endless tapes and suitably disposed rollers for directing the said sheets correctly through the machine.

The sheets of paper to be printed upon 30 are supported on an overhead feed table from which they are taken consecutively and passed to the printing cylinder by any well known and efficient feed mechanism.

The topmost sheet is passed by a feed 35 roller between endless tapes which direct the sheets through the printing sets and cutting devices, in the direction indicated by the arrows shown in Figure 7.

In the foregoing specification I have de- 40 scribed and in the drawings I have shown a press fitted with two printing sets and four inking sets but it will be readily understood that the press can be readily designed to take more than two printing sets and less or more 45 than four inking sets and therefore, I do not wish to be understood as limiting myself to the positive terms used in the description excepting such as the state of the art may require:

50 I claim:—

1. A printing press comprising two or more sets of printing cylinders, a reciprocating table supporting a plurality of forms, a number of inking sets for said printing cylinders, means for passing the paper to and from one printing set to the other, and a guide roller located between the printing sets, whereby when the table is reciprocated one or more impressions will be applied to 55 different parts of the paper passing through the press, whereby when the paper has passed through the last printing set all of the different impressions will be arranged in correct registration thereon.

60 2. A printing press comprising two or

more sets of printing cylinders, a reciprocating table supporting a plurality of forms, a number of inking sets arranged in combination with the reciprocating table, means for passing the paper to and from one printing set to the other printing set, a guide roller for the paper located between the printing sets, and a roller arranged parallel with the guide roller, and adapted to insure the printing performed by both sets being placed 70 in accurate register on the paper.

3. A printing press comprising two or more sets of printing cylinders, a reciprocating table supporting a plurality of forms, a number of inking sets arranged in combination with the reciprocating table, means for passing paper to and from one printing set to the other printing set, a guide roller for the paper located between the printing sets, and an adjustable roller arranged parallel 80 with the guide roller to insure the printing performed by both sets being placed in accurate register on the paper.

4. A printing press comprising two or more sets of printing cylinders consisting of 90 a paper cylinder, and an offset cylinder movably supported beneath the paper cylinder, a reciprocating table supporting a plurality of forms, a number of inking sets arranged in combination with the reciprocating table, 95 and means for raising and lowering the offset cylinder to bring it in and out of contact with the paper cylinder.

5. In a printing press, the combination of 100 a plurality of printing sets, a frame for the printing sets, a reciprocating table in the frame for supporting a number of forms, tracks arranged longitudinally in the frame, rollers mounted on the table bearing on the tracks, and adjustable extensions for said 105 tracks arranged to project beyond an end of the frame to support the table thereat.

6. In a printing press having two or more sets of printing cylinders and a number of 110 inking sets arranged in combination with a reciprocating table supporting a plurality of forms, racks disposed longitudinally on the table, gearing mounted on the frame of the press and driven by the racks, a train of 115 gearing for transmitting motion from the rack to the printing sets, and means for resiliently supporting the gear wheels of said train.

7. In a printing press having two or more sets of printing cylinders and a number of 120 inking sets arranged in combination with a reciprocating table supporting a number of forms, tracks on the frame of the press, rollers adapted to support the table and run on the tracks, and folding extensions on the 125 tracks adapted to be placed to permit of the table being moved beyond one end of the press.

8. In a printing press as claimed in claim 1, means for supporting a reel of paper at 130

- one end of the press, rollers for guiding the paper from the reel through the press, a pair of feed rollers adapted to be driven alternately to continuously unwind the paper
- 5 from the reel, a table between the feed rollers and a printing set for supporting a looped portion of the paper and means for operating the guide and the feed rollers.
9. A printing press comprising two or
- 10 more sets of printing cylinders, a reciprocating table supporting a plurality of forms, a pair of feed rollers, a ratchet wheel on the spindle of one roller, and an oppositely disposed ratchet wheel on the spindle of the
- 15 other roller, sprocket wheels rotatably mounted on both spindles and having pawls adapted to engage the ratchet wheels, and
- means whereby when the sprocket wheels are driven alternately in right and left hand directions the feed rollers will operate to 20 feed the paper into the press.
10. A printing press comprising two or more sets of printing cylinders composed of a paper cylinder and an offset cylinder movably supported beneath the paper cylinder, 25 a reciprocating table supporting a plurality of forms, a number of inking sets arranged in combination with the reciprocating table, means for passing the paper from one printing set to the other, and a guide roller for 30 the paper located between the printing sets.

In testimony whereof he has affixed his signature.

VERE LOCKSLEY REEVE.
